UNITED STATES PATENT OFFICE

2,541,854

WATER AERATING DEVICE

Herman Bachli and Harry S. Shapiro, Chicago,
Ill., assignors to Chicago Specialty Mfg. Co.
Inc., Chicago, Ill., a corporation of Illinois

Application September 22, 1948, Serial No. 50,476

1 Claim. (Cl. 261—76)

1 Our invention relates to water aerating device device for aerating the water.

More specifically, our invention comprises a device adapted to be connected to an ordinary water faucet or tap by means of threaded connection therewith or by means of a suitable adaptor, the device being provided with aperture arrangements for introduction of air bubbles into the stream of water to accomplish the object of rendering the water substantially soft as will be evidenced when the hand is projected into the stream; also the object of increasing the volume of water while dissipating therefrom cloudiness and the objectionable tastes and odors of city water resulting from the use therein of chlorine.

An essential feature of our invention is the relation of the several parts constituting our device whereby the same can be manufactured at an economical cost and assembled and disassembled by one other than a skilled mechanic.

Another equally important object of the invention is the locating at the outlet of the device screen elements of relatively fine mesh arranged in opposed relation with respect to each other and dished in opposite directions to provide therebetween a mixing chamber from which the stream emits in an even flow with increased volume and without splashing.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is an elevational view illustrating one form of construction of our invention in attachment with a water faucet or tap;

Fig. 2 is a sectional detail view (less the tap) taken substantially on line 2—2 of Fig. 1;

Fig. 3 is a perspective view of the several parts of the device illustrated in Fig. 1 showing the same in exploded relation with respect to each other;

Fig. 4 is a top plan view of a connector ring employed in the device of our invention showing a modification over that employed in Fig. 1;

Fig. 5 is a sectional detail view of the same taken substantially on line 5—5 of Fig. 4;

Fig. 6 is a sectional detail view of a connector ring similar to that shown in Fig. 5 but showing a slightly modified form of construction;

Fig. 7 is a plan view of the same taken substantially on line 7—7 of Fig. 6;

Fig. 8 is a sectional detail view of an adaptor showing the same attached to a faucet; and

2

Fig. 9 is a side elevational view of the device illustrated in Fig. 1 showing the same attached to a faucet or water tap by means of the adaptor shown in Fig. 8.

Referring more specifically to the form of the invention shown in Figs. 1 to 3 inclusive, we provide a connector ring 10. This connector ring 10 intermediate its end portions is provided with a transversely extending web 11. Either formed as an integral part of this web or as a separate unit for frictional connection thereto by projection through a centrally located opening 12 formed in the web, is a tube 13 closed at one end as at 14.

This tube 13 is cylindrical in form and is provided in its cylindrical walls with a number of elongated openings 15. These openings 15 extend above and below the web 11 for the passage of water from the chamber 16 provided above the web 11, through the tube 13 and into the chamber 17 provided by an intermediate ring 18.

This ring 18 provides a threaded neck 19 which is threaded into the connector ring 10. Below this neck 19 is provided an annular flange 20. At 25 the junction between this flange 20 and the neck 19 are provided a number of spaced elongated slots 21.

The flange 20 provides an upper tapered surface 22 which telescopes into the ring 10 and provides together with the bevelled edge portion 23 of the ring 10 an annular inlet 24 through which air is drawn for passage through the openings 21 for mixing with the water flow through the chamber 25 provided by the intermediate ring 18.

Below this flange 20 the ring 18 provides a thread-bearing end portion 26. On this end portion 26 is threaded a nozzle 27. The nozzle 27 provides an annular groove 28 within which is arranged a pair of screen elements 29 preferably of a finely woven mesh wire arranged in suitable frames.

These screens are superimposed with respect to each other and are formed dish-shaped in opposing relation to provide therebetween a chamber 30 to break up the flow of water through the device.

In the form illustrated in Figs. 1 to 3 inclusive, the connector ring 10 provides screw-threads 31 for threaded connection directly to the faucet or water tap 32.

The connector ring 10a illustrated in Figs. 4 and 5 is substantially the same as that illustrated in Fig. 2 with the exception that there is provided in the top wall of the tube 13a, a transversely extending groove 33 with the bottom of this groove provided with spaced apertures 34,

the latter to serve as inlets to the tube 13a in addition to the elongated openings 15a of the tube 13a.

In the form of the connector ring illustrated in Figs. 6-7, the top wall 36 of the tube 13b at its peripheral edge is provided with notches 37 which communicate with the interior of the tube 13b and are located between the elongated openings 15b of the tube 13b. The connector 10b shown in Figs. 6 and 7 is otherwise identical to that shown in Figs. 3 and 4.

When the device as illustrated in Fig. 2 is connected to the water faucet or tap 32 in the manner shown in Fig. 1, there is provided between the end of the tap 32 and the web 11 a rubber washer 32' for sealing purposes.

In Figs. 8 and 9, I have illustrated the device shown in Fig. 2 connected to an adaptor. This adaptor is indicated at 39. It includes a sleeve 40 into which the end of the faucet or tap 32a extends. The opening of the sleeve 40 into which this faucet 32a extends is of a diameter such as will permit faucets or taps of various diameters to be received in the opening 40. The adaptor 39 is connected to the water faucet or tap by set screws 41. Arranged in the base of the opening is a rubber washer 42 and threaded against this washer 42 is the end portion 43 of a connector 44 threaded into the sleeve 39 as shown in Fig. 8. This connector 44 has a threaded end portion 45 onto which is adapted to be threaded the connector ring 10.

It will be noted that in Fig. 2 that the air intake 24 is tapered downwardly and outwardly with respect to the device. This arrangement prevents any direct lateral spray should for any reason the water pressure be caused to back up into the device.

The flow of the water is through the elongated openings 15 of the device shown in Figs. 1 to 3 inclusive into and through the tube 13, into the chamber 25 and thence through the screens 29 and finally through the nozzle 27. As the water flows in this course under pressure, an aspirating effect is provided whereby air is drawn through the intakes provided by the annular groove 24 and the openings 21 into chamber 25 and becomes intimately mixed with the water stream to accomplish the several objects hereinbefore set forth.

In the form shown in Figs. 4 and 6, the course of the water before passing into the tube is through the openings 34 and 37 respectively of the device illustrated in these two figures, the operation and result, however, is substantially the same as that accomplished by the device shown in Fig. 2.

While we have illustrated and described the preferred form of construction for carrying our invention into effect, this is capable of variation and modification without departing from the spirit of the invention. We, therefore, do not wish to be limited to the precise details of construction set forth, but desire to avail ourselves of such variations and modifications as come within the scope of the appended claim.

Having thus described our invention, what we claim as new and desire to protect by Letters Patent is:

A device for intimately mixing air with a flowing stream of water comprising a connector ring for connecting the device to a water faucet, said ring having an internal web and a tube closed at one end, the latter supported concentrically within the ring by said web with the closed end of the tube adjacent the inlet end of the ring and above the web, said tube below its closed end having elongated openings formed in its side walls opening communication between the tube and the ring on opposite sides of the web, an intermediate ring having one end portion threaded into said connector ring and having an exterior portion providing a flange forming, together with a tapered edge of the connector ring, a downwardly and outwardly extending annular air groove, said intermediate ring being provided with lateral openings communicating with said groove, the open end of said tube extending below the plane of said lateral openings and within said intermediate ring, a nozzle threaded upon the exterior end portion of said intermediate ring, and screen members of finely woven mesh disposed between said nozzle and said intermediate ring, said screen members being concave in opposite directions with respect to each other and in spaced relation to provide there-

between a chamber.
